(57) **CLAIM**

The ornamental design for a charging case with microphones, as shown and described.

DESCRIPTION

FIG. 1 is a perspective view in the used configuration with the three parts assembled together of a charging case with microphones, showing my new design;

FIG. 2 is a perspective view of the charging case with microphones thereof, shown in a position of separation;

FIG. 3 is a front, left and top perspective view of a first component of the charging case with microphones;

FIG. 4 is a rear, right and bottom perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and

FIG. 10 is a bottom plan view thereof.

FIG. 11 is a front, left and bottom perspective view of a second component of the charging case with microphones;

FIG. 12 is a rear, right and top perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof; and

FIG. 18 is a bottom plan view thereof.

FIG. 19 is a front, right and bottom perspective view of a third component of the charging case with microphones;

FIG. 20 is a rear, left and top perspective view thereof;

FIG. 21 is a front view thereof;

FIG. 22 is a rear view thereof;

FIG. 23 is a left side view thereof;

FIG. 24 is a right side view thereof;

FIG. 25 is a top plan view thereof; and

FIG. 26 is a bottom plan view thereof.

The broken lines shown in the drawings illustrate portions of the charging case with microphones that form no part of the claimed design.
